Specification for Design.

Patented Sept. 9, 1913.

Application filed June 25, 1913. Serial No. 775,806. Term of patent 7 years.

To all whom it may concern:

Be it known that I, EDWIN A. BYE, a citizen of the United States, residing at Owatonna, in the county of Steele and State of Minnesota, have invented a new, original, and ornamental Design for a Churn-Frame, of which the following is a specification, reference being had to the accompanying drawing, forming part thereof.

Figure 1 is a side view of the churn

frame showing my design; and Fig. 2 is an edge elevation of the same.

I claim:

The ornamental design for a churn frame, as shown.

EDWIN A. BYE.

In the presence of—

CARL K. BENNETT,

R. W. PANATT.
